(57) **CLAIM**

The ornamental design of casing centralizer having straight blades, substantially as shown and described.

DESCRIPTION

FIG. 1 is a perspective view of a casing centralizer having straight blades showing our new design;

FIG. 2 is a rear elevational view thereof;

FIG. 3 is a front elevational view thereof;

FIG. 4 is a right-side elevational view thereof;

FIG. 5 is a left-side elevational view thereof;

FIG. 6 is a top plan view thereof; and,

FIG. 7 is a bottom plan view.

The broken lines showing a cylinder are included for the purposes of illustrating only and form no part of the claimed design.
